CLAIM

The ornamental design for an inkball with a hole, as shown and described.

DESCRIPTION

FIG. 1 is a top plan view of an inkball with a hole showing our new design;

FIG. 2 is a front right perspective view thereof;

FIG. 3 is a bottom plan view thereof;

FIG. 4 is a right side view thereof, the left side, front and rear views being identical thereof;

FIG. 5 is a sectional view thereof, taken along line 5—5 of FIG. 1; and,

FIG. 6 is a sectional view thereof, taken along line 6—6 of FIG. 1.
